G. BLYBERG

SAFETY ENVELOPE

Filed Sept. 13, 1922

Inventor
George Blyberg

By *John T. Talbot*
Attorney

UNITED STATES PATENT OFFICE.

GEORGE BLYBERG, OF REEDSPORT, OREGON.

SAFETY ENVELOPE.

Application filed September 18, 1922. Serial No. 587,961.

To all whom it may concern:

Be it known that GEORGE BLYBERG, a citizen of the United States of America, residing at Reedsport, in the county of Douglas and State of Oregon, has invented new and useful Improvements in Safety Envelopes, of which the following is a specification.

The object of the invention is to provide a simple and efficient construction of safety envelope having sealing means which prevent the opening of the envelope without detection; and with this object in view the invention consists in a construction and combination of parts of which a preferred embodiment is shown in the accompanying drawings, wherein:—

Figure 1 is a view of an envelope embodying the invention as seen when closed and sealed.

Figure 2 is a rear view of the same.

Figure 3 is a view of the blank from which the envelope is formed and having indicated thereon the gummed surfaces.

The envelope consists of the main panel 10 from the side edges of which extend the bottom flap 11 and the cover flap 12 while from the end edges thereof extend the end flaps 13 and 14. In the formation of the envelope the back flap is folded into overlapping relation with the main panel and the end flap 13 which is of less length than the flap 14 and which is provided with an intermediate gummed surface 13^a is folded over the back flap and secured while the end flap 14 which is gummed at its edges as indicated at 14^a is folded over the back flap

and the end flap 13 and secured to both through the agency of said gummed edges.

The cover flap 12 is gummed throughout its side and end edges as indicated at 12^a to adhere to the exposed rear surfaces of the back and both end flaps, and in addition the cover flap carries at one end a locking tongue 15 gummed throughout its inner surface and adapted to be folded around the envelope adjacent to one end and to be terminally sealed to the front or main panel by a postage stamp 16 which is of a width greater than said tongue to overlap the same and thereby adhesively engage the surface of the main fold.

Having described the invention, what is claimed as new and useful is:—

A safety envelope consisting of a main panel provided with bottom and cover flaps at its side edges and end flaps at its end edges, one of said end flaps being of shorter length than the other and provided with an intermediate gummed surface inset from its edges, the longer of said end flaps having a gummed edge surface at its free edges, the cover flap having a gummed surface at its free edges and being provided with a tongue at one end extending perpendicularly to the length of the main panel and of a length, when the cover flap is folded, to extend around the lower edge of the main panel and across the front face of the latter to terminate within the stamp receiving area.

In testimony whereof he affixes his signature.

GEORGE BLYBERG.
